VIBRATED CONVEYER FEEDER

Andrew T. Hendrix, Knoxville, Tenn.

Application July 20, 1936, Serial No. 91,634

4 Claims. (Cl. 83—44)

(Granted under the act of March 3, 1883, as amended April 30, 1928; 370 O. G. 757)

This application is made under the act of March 3, 1883, as amended by the act of April 30, 1928, and the invention herein described, if patented, may be manufactured and used by or for the Government for governmental purposes without the payment to me of any royalty thereon.

This invention relates to a process of and apparatus for controlling the amount of feed delivered by a vibrated conveyer feeder.

10 One of the objects of this invention is to provide a means for charging a material continuously and uniformly with a minimum of attention by the operator. Another object of this invention is to provide a means of control for the amount of charge delivered by either a mechanical or an electrical vibrated conveyer. Other objects of this invention include the provision for control of a charge in order to produce a maximum output with any given size of motor.

20 I have discovered an effective means for charging grinding mills and other devices into which a feed must be admitted either at a uniform rate or under definitely controlled circumstances, taking into account variations in the character of the charge, by controlling the operation of a vibrated conveyer feeder by means of a solenoid actuated directly or indirectly by the current demand of the electric motor which is used as the prime mover for the device which is being fed.

30 In the accompanying drawings, which form a part of the specification, and wherein reference symbols refer to like parts whenever they occur,

Fig. 1 is a diagrammatic, vertical, sectional view of one form of apparatus for the embodiment of my invention in a hammer mill,

Fig. 2 is a diagrammatic, plan, sectional view of the apparatus shown in Fig. 1,

Fig. 3 is a somewhat enlarged diagrammatic, vertical, sectional view of the vibrated conveyer feeder and associated controlling mechanism,

Fig. 4 is a diagrammatic, plan, sectional view of the somewhat enlarged diagrammatic, vertical, sectional view of the vibrated conveyer feeder and associated controlling mechanism as shown in Fig. 3.

In Fig. 1, the hammer disc 1, to which hammers, represented by hammer 3, are attached, is rotated at the appropriate speed by the electric motor 5. The charge to the hammer mill is admitted through the inlet 7, onto the mechanically vibrated conveyer screen feeder 9. The feeder 9, is supported at four points by stiff wire members, represented by supports 11. The charge which has been advanced to the end of the feeder 9, drops into the body of the hammer mill and is

pulverized by the successive impacts with the hammers, represented by hammer 3. The material which has been reduced to a sufficient fineness drops out of the mill through the screen 13. It is necessary to regulate the flow of charge delivered by the feeder 9, first in order to prevent overloading the motor 5, and second, in order to maintain a sufficiently high rate of charge so that the maximum efficiency may be obtained from the motor 5. This regulation of the discharge of charge from feeder 9, is obtained by the use of the dampener 15, the ends of which are attached to the main body of the mill and the base attached to the core of the solenoid 17. In normal operation, the shoes of the dampener 15, located between the ends and the base, press lightly on the sleeve welded to the underneath side of the feeder 9, through which passes the shaft of the mechanical vibrator. If the amount of charge delivered to the body of the mill gradually exceeds the normal amount of charge, the motor 5, gradually approaches an overloaded condition, under which condition considerable additional current is required to operate the motor. The solenoid 17, is wired in series with the motor 5, so that as the load on the motor 5, approaches the full load capacity of the motor, the solenoid 17, gradually actuates the dampener 15, thereby reducing the amount of charge delivered by the feeder 9. Thus a continuous adjustment takes place so that at all times the maximum amount of charge is being admitted into the body of the mill with the resulting maximum efficiency of operation without constant personal attention of the operator.

35 In Fig. 2, the ends of the dampener 15, are shown attached to the frame of the mill at points 19, the base of the dampener 15, is shown attached to the core 21, of the solenoid 17.

In Fig. 3, one end of the dampener 15, is shown attached to the frame of the mill at points 19. 40 The base of the dampener 15, is shown attached to the core 21, of the solenoid 17. The core 21, of the solenoid 17, is supported by an adjustable spring device 22, in order that the dampener or braking means may be properly adjusted to normal conditions of operation. The shoes 23, of the dampener 15, contact the sleeve 25, which serves as a bearing for the shaft 27, of the mechanical vibrator, the principal element of which is the unbalanced pulleys, represented by pulley 29. The solenoid 17, is shown wired in series with the motor 5.

45 In Fig. 4, the ends of the dampener 15, are shown attached to the frame of the mill at points 19, and the base of the dampener 15, is shown

attached to the core 21, of the solenoid 17. The shoes 23, of the dampener 15, contact the sleeve 25, which serves as a bearing for the shaft 27, of the mechanical vibrator, the principal element of which is the unbalanced pulleys 29.

It is evident that there are numerous factors which will influence conditions for the most satisfactory operation of my invention, the actual limits of which cannot be established except by a 10 detailed study of each installation involved.

The vibrated conveyer feeder may be actuated by either an electrical or mechanical means. The examples of vibration of the conveyer feeder by mechanical means include the use of rotating off- 15 balance pulleys or rotating cams.

The vibrated conveyer feeder may be used in conjunction with any mechanical device which requires power for its operation, such as, grinders, mixers, or even other conveyers. In the 20 operation of this invention it is necessary that the conveyer be operated by means of an electrical motor since the control of the feeder is effected by taking advantage of the change in current demand of the motor which is used as 25 the prime mover.

The control of the vibrated conveyer feeder is effective by the use of a vibration dampener with the degree in which this dampener is applied changing the amplitude of the vibration 30 of the feeder and thereby regulating the amount of the feed discharged. The dampener actually may be constructed in a variety of forms, including a simple braking device, a device which will retard the motion of the feeder in one di- 35

rection, or a device which may retard the motion of the feeder in both directions. The dampener is constructed so that one and both the ends are secured to the frame of the machine and the other end or the center where the device is 40 somewhat U-shaped, is connected to the core of a solenoid. The controlling means proper, mentioned above, are located intermediate between the attachment to the frame and the core of the solenoid. The core of the solenoid is supported 45

by an adjustable spring device in order that the dampener or braking means may be properly adjusted to normal conditions of operation.

The vibration control or braking means is actuated by the solenoid. The solenoid may be 50 wired in series with the electric motor and thereby directly influenced by the amount of the current which passes through it. The variation in current demanded by the motor may be used to operate a relay which, in turn, regulates the 55 current required to operate the solenoid independent of the current supply of the motor.

It will be seen, therefore, that this invention actually may be carried out by the modification

of certain details without departing from its spirit or scope.

I claim:

1. In an apparatus for continuously comminuting a charge, the combination which comprises, 5 a hammer mill, a vibrated conveyer feeder for charging the hammer mill, an electric motor for driving the hammer mill and for vibrating the conveyer feeder, and a means for dampening the vibrations of the vibrated conveyer feeder, said means comprising a solenoid having a core, the coil of the solenoid being wired in series with the electric motor and the core of the solenoid connected to the vibrating conveyer feeder to vibrate therewith and to automatically and continuously control the amount of charge to the mill. 15

2. In an apparatus for continuously comminuting a charge, the combination which comprises, a mill, an electric motor for driving the mill, a 20 vibrated conveyer feeder for charging the mill, and a means for dampening the vibrations of the vibrated conveyer feeder, said means comprising a solenoid having a core, the coil of the solenoid being wired in series with the electric 25 motor and the core of the solenoid connected to the vibrating conveyer feeder to vibrate therewith and to automatically and continuously control the amount of charge to the mill.

3. In an apparatus for feeding materials from a vibrated conveyer feeder to a device operated by an electric motor, the combination which comprises, an electric motor for driving the device, a vibrated conveyer feeder, and a means for dampening the vibrations of the vibrated conveyer 30 feeder, said means comprising a solenoid having a core, the coil of the solenoid being wired in series with the electric motor and the core of the solenoid connected to the vibrating conveyer 35 feeder to vibrate therewith and to automatically 40 and continuously control the amount of charge to the device being fed.

4. In an apparatus for feeding materials from a vibrated conveyer feeder to a device operated by an electric motor, the combination which 45 comprises, an electric motor for driving the device, a vibrated conveyer feeder, and a means for dampening the vibrations of the vibrated conveyer feeder, said means comprising an electro-magnet having a coil element and a core 50 element, the coil element of the electro-magnet being wired in series with the electric motor and one of the said elements of the electro-magnet being connected to the vibrating conveyer feeder to vibrate therewith and to automatically and 55 continuously control the amount of charge to the device being fed.

ANDREW T. HENDRIX.
